UNITED STATES PATENT OFFICE.

FRANK DUTCHER, OF VERSAILLES, PENNSYLVANIA, ASSIGNEE OF ONE-HALF TO
ALLEN S. PATTISON, OF WASHINGTON, DISTRICT OF COLUMBIA.

SHELL FOR DYNAMITE OR OTHER EXPLOSIVES.

1,147,622.

Specification of Letters Patent. Patented July 20, 1915.

Application filed November 4, 1912. Serial No. 729,519.

To all whom it may concern:

Be it known that I, FRANK DUTCHER, a citizen of the United States, residing at Versailles, in the county of Allegheny and 5 State of Pennsylvania, have invented certain new and useful Improvements in Shells for Dynamite or other Explosives, of which the following is a specification, reference being had therein to the accompanying 10 drawing.

My invention relates to improvements in shells for dynamite or other explosives, and the principal objects of my present invention are: 1. To produce a shell so constructed 15 that when filled with the explosive an opening is formed in the explosive within the shell to receive either the detonating cap and fuse, or an electric fuse, thus avoiding the necessity of the user drilling an 20 opening in the explosive with its consequent danger for the reception of the detonating cap or fuse, thus eliminating this dangerous feature in the use of dynamite sticks as now furnished to the consumer. 2. To produce 25 an absolutely waterproof shell before the explosive is placed therein, to avoid a dipping of the charged shell in hot paraffin wax with its consequent danger, which is the custom to-day in waterproofing dynamite or 30 other explosive shells. 3. To positively seal both ends of the shell and thereby positively prevent any leakage of the explosive from the shell while in transportation or storage with the consequent danger, which leakage 35 sometimes happens with the dynamite and explosive shells as now manufactured and sold, and in practice this defect sometimes causes serious explosions either in transportation or storage, or both. 4. To produce 40 a shell which is safe in transportation and storage and prevents jar directly on the ends of the explosive during transportation and which is also so constructed that when the fuse is placed within the shell by the 45 user the fuse can be locked therein and the stick let down in the hole provided to receive it without any danger of the fuse becoming disconnected, and, in fact, which will permit the shell or stick to be lowered 50 by the fuse without any danger of disconnecting the latter from the shell.

Dynamite and explosive shells as manufactured and sold to-day and as known to me, consist of a paper tube having open 55 ends. The tube is filled with this dynamite,

after which a sheet of paper wider than the length of the tube is rolled around the shell with both ends extending beyond the end of the tube or shell containing the dynamite. These extended paper ends are folded in 60 over the dynamite or explosive in the shell and folded and pasted to hold the dynamite therein. The shell or tube being thus charged with dynamite or explosive, the whole is dipped into a hot solution of 65 paraffin wax which involves some danger from the heat of the wax. Furthermore, when this shell or stick of dynamite is thus waterproofed and delivered in this form to the user, it is necessary for the user to drill 70 or cut out an opening in the dynamite large enough to receive the detonating cap or fuse, or both, which under certain conditions is dangerous and liable to cause premature explosion. The shell which is now furnished 75 loaded with dynamite is of a flimsy nature and the dynamite being of a greasy character, the folded paper ends of the shell are frequently burst open and the dynamite leaks or sifts out, making it unsafe for 80 transportation or storage, which defect has been the cause of some serious explosions.

My present improvement is to overcome the foregoing undesirable features of the dynamite sticks or shells as now manufactured and sold to the consumers.

In the accompanying drawings—Figure 1 is a perspective view of a charged dynamite or explosive shell with the fuse therein ready to be used. Fig. 2 is a perspective 90 view of the fuse receiving end of my improved explosive shell, showing the screw cap removed and wood pin in the act of being removed for the reception of a detonating cap and fuse. Fig. 3 is a sectional 95 view of the fuse end of my improved dynamite or explosive shell, showing the parts in position as manufactured and sent to the consumer. Fig. 4 is a longitudinal central sectional view of my improved dynamite or 100 explosive shell, showing it charged as manufactured and sold and in an inverted position. Fig. 5 is a sectional view of my improved dynamite or explosive shell, showing the detonating fulminate or cap and also the 105 fuse in position. Fig. 6 is a similar view showing an electric fuse applied to my improved dynamite or explosive shell, and a slight modification of the screw cap.

In carrying out my invention, I provide 110

a fiber tube 1, of substantial character, and this tube in the process of manufacture has one end 2 turned or crimped inward, leaving a central opening 3. A wood member or 5 plug 4 is provided and this plug consists of a flange *a* and a projection *b*, the projection *b* extending through the opening 3 and externally screw-threaded at *c* to receive an internally screw-threaded cap 5. The projection *b* has an opening *d*, and the screw-cap 5 an opening *e* which is in a line with the said opening *d*. This member 4 is then placed in the shell or tube 1 in the position shown. The tube with the member 4 in position 10 therein is then placed in melted paraffin wax and boiled a sufficient length of time to waterproof the shell and the wood member. This having been done, a pin 6 with a head 15 is placed with the pin portion through the opening *d* in the projection *b*, and the screw-cap 5 screwed thereon which holds the pin 6 in position. The pin and the screw-cap are first waterproofed with paraffin before they are placed in position on 20 the shell.

With the parts in the position shown in Fig. 3, the tube is inverted as shown in Fig. 4 and the explosive charge 8 placed therein, the pin 6 making a hole in the charge for 25 a purpose to be presently described.

In Fig. 6 I have shown a slight modification in that the screw-cap 5', there shown is made of metal instead of wood, as in the other figures of the drawings. The shell 30 being charged, a cup-shaped paraffin disk 9 is placed and cemented in the bottom of the tube 1, and preferably further secured therein by turning the projecting end 10 of the tube inward and around the disk, as 35 shown in dotted lines 11.

The shell being manufactured and sold in the form shown in Fig. 4, the user removes the screw-cap 5, and removes the pin 6. The screw-cap is replaced and the detonating 40 cap or fulminate 12 is inserted in the opening *f* formed in the charge 8 by the pin 6, and at the inner end of the opening. The fuse *g* is then inserted through the opening in the cap and the opening in the projection 45 *b*, as shown in Fig. 5. If desired, the fuse may be placed in position before the cap is placed thereon, and a wrapping of string or tape *h* placed around the fuse at the outer end of the projection *b* and then the cap 50 placed in position. This arrangement will lock the fuse in position so that it cannot become detached, and which will enable the fuse, if desired, to be used as the means of lowering the shell into the hole made in 55 the ground or other thing or substance to be subjected to the explosive force of the shell.

In Fig. 6 I have shown the improvement with the usual electric fuse *i* applied thereto. 60 A dynamite shell, constructed as herein

shown and described, will be safe in the hands of the user; safe in transportation and in storage and while the expense of construction may be slightly increased over the form of shell as now manufactured and sold, 70 yet the plug and cap can be very cheaply made and will not increase the cost of manufacture much, and at the same time will make the shell or stick safe, as above explained, which is by far a more important 75 factor than any slight increase in the cost of manufacture occasioned by the use of this improvement. The improvement will protect the manufacturer; will protect the person and property used in transporting it, 80 and will afford a protection to persons and property while in storage all of which are of paramount importance.

Having thus described my invention, what I claim and desire to secure by Letters Patent is:

1. An explosive shell comprising a tube having a closure for its bottom, a closure for its fuse receiving end, said closure having an opening, a removable pin passing 90 through the opening and into the shell for the purpose described, and means for holding the pin in position.

2. An explosive charge comprising a tube having a closure at its bottom, a plug at 95 its opposite end, the said plug having a fuse receiving opening, a removable member adapted to pass through the said opening into the explosive charge for the purpose described, and a removable cap interlocking 100 with the plug to hold the removable member in position.

3. An explosive shell comprising a tube having a closure at one end, the opposite end having a fuse receiving opening, a removable member adapted to pass through the opening and into the explosive charge for the purpose described, and a removable cap adapted to lock the removable member in position.

4. An explosive shell comprising a tube having a closure at one end, the opposite end having a fuse receiving opening, a removable member passing through the opening into the explosive charge for the purpose described, a removable cap for holding the removable member in position, the cap having an opening registering with the fuse receiving opening for the purpose described.

5. An explosive shell comprising a tube 110 having a closure at one end, the opposite end having a plug with a projection, the plug and projection having a fuse receiving opening, a removable member passing through the opening and into the explosive 115 charge, and a removable cap removably engaging the said projection for holding the removable member in position.

6. An explosive receiving shell, comprising a tube having a firm bottom closure, the 120

opposite end of the tube having an inwardly extending flange leaving a central opening, a removable pin passing through the opening to form a fuse receiving opening in the explosive charge, and removable means clamped to the said flange for removably holding the pin in position.

7. An explosive containing shell, comprising a tube having a closed bottom, the opposite end of the tube having an inwardly extending flange, a member at the inner side of the flange, said member having an opening, a removable pin passing through the opening and into the tube for the purpose described, and a removable cap interlocking with said member and holding the removable pin in position.

8. An explosive receiving shell, comprising a tube having a closed bottom, the op-

posite end of the tube having an inturned flange, a member within the tube and engaging the inner side of the flange, a removable cap outside of the flange and interlocking with the said member and clamping the flange between the member and cap, said member and cap having registering openings, a removable pin passing through the opening of the member and into the tube for the purpose described, the pin having a flange at its outer end, and the cap locking so the flange between the member and the cap all combined for the purpose described.

In testimony whereof I hereunto affix my signature in the presence of two witnesses.

FRANK DUTCHER.
